UTILITIES MODULE FOR AIRCRAFT CABIN INTERIOR

Richard W. Kraus, Claymont, and Jules G. Rondepierre,
Wilmington, Del., assignors to Atlantic Aviation Cor-
poration, Wilmington, Del., a corporation of Delaware

Filed Dec. 13, 1967, Ser. No. 9,763

Term of patent 14 years

U.S. Cl. D71—1
Int. Cl. D12—07

FIG. 1 is a front view in elevation of a utilities module for aircraft cabin interior showing our new design;

FIG. 2 is a right end elevational view thereof, the left end being identical, but opposite hand, with adjacent interior wall shown in phantom outline for illustrative purposes only;

FIG. 3 is a top plan view thereof;

FIG. 4 is a front elevational view of a slight modification of the module shown in FIG. 1;

FIG. 5 is a cross-sectional view of FIG. 1 taken along the line 5—5 with adjacent interior wall shown in phantom outline for illustrative purposes only; and

FIG. 6 is a cross-sectional view taken along the line 6—6.

We claim:

The ornamental design of utilities module for aircraft cabin interior, as shown and described.
